Technical drawing of a mechanical device, labeled Fig. 2, showing various mechanical components and labels A through Z.

The drawing illustrates a complex assembly of mechanical parts, including:

- A main circular base or frame.
- A central vertical column with a gear assembly.
- Various levers and connecting rods labeled with letters A through Z.
- Labels A through Z are placed near specific components: A, B, C, D, E, F, G, H, I, J, K, L, M, N, O, P, Q, R, S, T, U, V, W, X, Y, Z.
- Labels A' through Z' are placed near other components: A', B', C', D', E', F', G', H', I', J', K', L', M', N', O', P', Q', R', S', T', U', V', W', X', Y', Z'.
- Labels A'' through Z'' are placed near yet other components: A'', B'', C'', D'', E'', F'', G'', H'', I'', J'', K'', L'', M'', N'', O'', P'', Q'', R'', S'', T'', U'', V'', W'', X'', Y'', Z''.

UNITED STATES PATENT OFFICE.

PLINY F. HODGES, OF CHICAGO, ILLINOIS.

GRAIN-BINDING HARVESTER.

SPECIFICATION forming part of Letters Patent No. 319,717, dated June 9, 1885.

Application filed November 10, 1880. (Model.)

To all whom it may concern:

Be it known that I, PLINY F. HODGES, residing at Chicago, in the county of Cook and State of Illinois, and a citizen of the United States, have invented new and useful Improvements in Grain-Binding Harvesters, of which the following is a full description, reference being had to the accompanying drawings.

This invention relates to that type of self-binding harvesters designated as "low-down" binders—from the circumstance that the cut grain is delivered to the self-binder and bound thereby at about the level of the grain-platform—as distinguished from the type in which the cut grain is elevated over the main or drive wheel of the machine before delivery to the binder.

My invention consists, mainly, in organizing the machine with alternately-operating packers, which take the loose grain and pack it against the binding cord or wire into a distinct gavel at a point on the low-down binder-table beyond where the point of the binding-arm, in completing the encompassment of the gavel with the binding cord or wire, crosses the plane of such binder-table, so that the binding-arm strikes not through a heaped-up mass of gathered grain from which to divide sufficient for a gavel, but through a comparatively thin sheet of loose grain to operate on an already formed compacted gavel. By this organization I have practically effected the necessary separation of the gavel and bundle from the inflowing grain, so difficult in low-down binders, while also obviating the objectionable penetration of a heaped-up mass of grain by the binding-arm.

My invention further consists of the combination, with the packers, of a binding-arm which operates with a raking action across the low-down binder-table after the encompassment of the gavel with wire or cord and during the securing of the ends of the band, so as to rake the compacted bundle away from the packers, and thus provide a wide open space between it and the packers for the accumulation of grain for the next bundle, and after the gavel is bound returns over the accumulated grain to its first position.

My invention further consists of other novel

mechanical combinations, which, together with the above, will be properly described in the succeeding portion of this specification, and specifically pointed out in the claims at the close thereof.

In order that my invention may be clearly understood, I have illustrated in the annexed drawings, and will proceed to describe, one practical form thereof.

Figure 1 is a plan view of the machine, the binding-arm, seat, and portions of the reel and tongue being omitted or broken away. Fig. 2 represents the stubble side of the machine in elevation. Fig. 3 is a front elevation of the machine, the reel, cutter-bar, and grain-platform being omitted. Fig. 4 is a vertical transverse section of the machine in planes indicated by the line $\alpha\alpha$ in Fig. 1. Figs. 5 to 14 illustrate various details of the machine.

The same letters of reference are used in all the figures to designate identical parts.

The main frame F is pivoted by a sleeve, through which the cross main shaft P, journaled in suitable bearings, P' P', on the forward end of the main frame, passes to a forwardly-projecting crank-arm on the loose axle of the main or drive wheel W. The tongue W' is rigidly secured to a casting pivoted to the forward end of the main frame and carrying a cross rock-shaft connected by a link to the main frame. By means of a lever, X, secured to said rock-shaft the main frame and all the parts connected therewith and supported thereon can be tilted for proper adjustment of the cutting apparatus. When the proper adjustment has been made, the lever X is locked by the usual spring-latch device to a rack rigidly connected with the tongue-casting. The bar W' of the seat is pivoted to a part of the seat-casting, and connected to the axle of the drive-wheel on the outside thereof in the usual manner.

There is nothing new in the construction and combination of these parts as far as described.

I elongate the seat-bar rearwardly, so that the seat will beat a point from which the driver can watch all the operations of the machine, and reach over from his seat to pull out any bundle that may happen to stick in the binder.

This thus rearwardly-extended seat, as combined with other parts to be described herein-after, forms one of the minor novel features of my invention.

5 The main frame terminates at its rear end at a line a little in rear of the axle of the drive-wheel, and its rear edge, at least that portion thereof which is between the drive-wheel and the low-down binder-table A", is on about a 10 line with the front edge of the grain-platform A, so that the cut grain may be moved squarely across the grain-platform into the binder-table and the bundle discharged in the same direction from the binder without danger of lodging, with the stubble end on the main frame. The space between the drive-wheel and the adjacent edge of the low-down binder-table is 15 of sufficient width to afford a free discharge of the bundle. Heretofore it has been customary to have between the drive-wheel and the adjacent edge of the binder-table a rearwardly-extending main frame-beam and a cross-beam at the rear end thereof for the purpose of supporting the rear end of the 20 grain-platform. Such construction is objectionable because it is apt to interfere with the discharge of the bundles. Hence I dispense with such beams, so that the bundles can be discharged wholly outside of the frame-work 25 of the machine, and support the grain-platform in an overhung manner from the finger-beam D, to which it is rigidly secured. The inner shoe, D', of the finger-beam is in turn rigidly secured to the main frame. The grain- 30 platform is provided with the usual divider, Z, and the usual grain-wheel is connected with the outer shoe of the finger-beam.

The shaft V of the reel, which latter is composed of the head V', arms V", and blades V³, is 40 journaled in the forwardly-projecting arms U" of a rocking frame whose bar U' is supported in suitable bearings on top of the posts F' F", erected on the main frame. A lever, X', is fixed to the rocking frame, by which the latter 45 may be rocked for raising or lowering the reel. This lever carries the usual spring-latch for locking it to a fixed rack on one of the posts F'. The reel is driven by the chain-wheel T' on the main shaft P, through the intervention of the drive-chain T and the chain-wheel T" on the reel-shaft. The drive-chain T runs over guide-rollers journaled in a yoke, U, connected with the rocking frame which 50 supports the reel. These guide-rollers maintain the tautness of the drive-chain T in all 55 positions of the reel.

The main shaft P is driven by the internal gear, Q', of the drive-wheel W through the medium of the pinion Q, secured to the outer end 60 of the main shaft. The pitman S³, for reciprocating the cutter-bar, is driven by the crank-wheel S", fixed to the rear end of the crank-shaft, the forward end of which carries the bevel-pinion S', driven by the bevel-wheel S 65 on the main shaft P.

The grain-platform A is constructed just inside of the inner end of the finger-beam with

an elevated delivery-bridge composed of bars A', the upper horizontal portions of which are connected by inclined portions to the grain-platform. The elevated bridge is employed for the purpose of lifting the grain so that it may be bound at a level a little higher than that of the grain-platform, in order that the bundles may be discharged at a level a little 70 above the stubble. The spaces C' between these bars A' coincide with cross-slots C in the grain-platform. In these slots C' operate a series of carrying-bars, B, which are constructed with teeth formed as shown in Fig. 4. That 75 portion of each carrying-bar which operates in the slot C of the grain-platform A is approximately horizontal, while that portion which operates in the elevated bridge is inclined upward and provided with somewhat longer 80 teeth to facilitate the elevation of the grain onto the bridge. At the grain side of the platform the carrying-bars are supported by cross-pins in suitable guide-grooves, and at about the junction of the inclined and horizontal portions 85 they are connected, respectively, to the alternately-opposite cranks E' of a crank-shaft, E, located under the elevated bridge A'. The cranks E' impart alternating compound reciprocating 90 motions to the carrying-bars in such a manner that the greater portion of their teeth will be in the slots C' and below the surface of the grain-platform as they move toward the grain side of the platform, and all the teeth will be above the surface of the platform as they move 95 in the opposite direction. The carrying-bars 100 convey the grain across the platform up onto the elevated bridge thereof. The grain delivered on the elevated bridge is moved onto the low-down binder-table A", which adjoins the elevated delivery-bridge A', and packed 105 into a gavel against the binding wire or cord J', under the compressor-fingers Y', by the packers B'. Since these packers are required to operate alternately, and have substantially 110 the same motions as the carrying-bars, and since the packers require guided tails to maintain 115 them in proper relations to the cranks, the function of which tails can be performed by the carrying-bars, I have shown them in this example of my invention as formed on the extreme outer or stubble end of said carrying-bars. These packers thrust close up to the adjacent edge of the binder-table.

The compressor-fingers Y' are secured to a 120 suitable overhead support, Y.

The crank-shaft E, supported in suitable bearings on the grain-platform and the bearing E" on the inner shoe, D', of the finger-beam, projects beyond the end of the main 125 shaft P, by which it is driven through the medium of the bevel-gears R R'.

The low-down binder-table is composed of two parts separated by a cross-slot and secured upon a frame, K' K" K³, illustrated in 130 detail in Figs. 9 and 10. The main body K' of this frame has a cross-slot directly under the cross-slot of the binder-table, but is constructed with stirrups for rigidly connecting

the parts on opposite sides of said cross-slot. The forward ends of the arms K" K" of this frame are secured to the base H of the binder-frame, which base is mounted on longitudinal 5 tracks or ways G on the main frame F. The ways G terminate at about the rear edge of the main frame; but the binder-table is also supported and guided near its rear end by the rearwardly-projecting bar K³ of its frame, on a 10 bracket, K⁴, secured to the grain-platform. The binder-frame is composed of the base H, already referred to, the standard H', and tubular arm H", which projects from the standard in a rearward direction over the low-down 15 binder-table. The binding-arm J is pivoted on the crank I', on the rear end of the binder-shaft I, which is supported in the tubular arm H" of the binder-frame.

The binding arm shown is designed to carry 20 a wire-twister or cord-knotter in its point, which is slotted in order that the wire or cord may enter it. The wire or cord passes from a reel (not shown) to the twister or knotter in the binding-arm by way of the guide-roller 25 journaled in one of the stirrups of the binder-table frame, and a guide-roller journaled in the rocking tucker K, located in the cross-slot of the binder-table. This tucker is a skeleton beam, carrying said guide-roller at one 30 end, and is at one side secured to the rear end of the rock-shaft L, and is at the other side provided with a journal-pin, for additional support in frame K'. The front end of shaft L is provided with a crank, L', by which it is 35 rocked, whenever the binder-shaft rotates, from a crank, L³, on the front end of said binder-shaft, through the medium of a connecting-rod, L". The binding-arm is hung on the crank I', so as to operate in the vertical 40 plane of the cross slot of the binder-table, and between the side bars of the skeleton tucker, the guide-roller of which is just cleared by the point of the binding-arm in its descent. The movements of the binding-arm and tucker are 45 so timed that as soon as the point of the binding arm in its descent reaches about the level of the tucker the end of the latter, which carries the guide-roller, begins to ascend, so as to tuck the wire or cord into the slit in the 50 point of the binding-arm. This guide-roller end of the tucker, which reaches to about the inner edge of the binder-table, does not in ascending rise above the level on which the grain is moved by the packers, in order that 55 it may not obstruct the free movement of the grain onto the binder-table while a previously-formed gavel is being bound.

In order that the binding-arm may rake the 60 gavel across the binder-table during the operation of securing the band around such gavel, and thus provide a clear space behind it for the accumulation of grain for the next gavel, and that it may subsequently ascend and move over the accumulated grain to its 65 first position, I use a binding-arm constructed with a tail, J', connected with a radius-link, J", to a fixed bracket-arm, H³, on the tubular

arm H" of the binder-frame. The binding-arm is so located with reference to the packers B' that in descending to bind a gavel its 70 point reaches beyond the line to which the packers thrust the grain and passes through the loose grain on the delivery-bridge A'. To put it the other way, the packers thrust and compact the gavel beyond the point where 75 the point of the binding-arm passes through the flowing grain in descending to bind such compacted gavel. Since the binding-arm has a raking action across the binder-table, I also cause it to perform the function of discharging the bundle by extending its sweep to the outer edge of such binder-table. 80

The binder-frame, together with all the parts supported thereon, can be adjusted longitudinally of the machine on the ways G 85 of the main frame, and the binding-arm thereby located at any required point within certain limits along the side of the grain-platform, so that the gavels may be bound at such distance from the butt-end as the varying 90 lengths of grain may require. The adjustment of the binder must always be such, of course, that the binding-arm will clear the packers.

The bars of the bridge A' are forked at the 95 end adjacent to the binder-table, as shown in Fig. 1, so that the binding-arm may pass through such forks.

The binder is operated to bind successively-compacted gavels, one during each complete 100 rotation of the binder-shaft, by means of the chain-wheel M" on the main shaft P, through the medium of the drive chain M; chain-wheel M', mounted on a stud on the binder-frame, and bevel-wheels O O', the wheel O being secured to the chain-wheel M' and the wheel O' to the binder-shaft I. Chain-wheel M" is normally locked to the shaft by means of a spline or pin, with which it is held engaged by a spring coiled around said shaft, but may be 105 slid thereon to unlock it whenever the binder requires to be stopped.

A suitable lever or other device arranged to be within reach of the driver is to be provided for sliding the chain-wheel M" to unlock it from the main shaft. 115

The drive-chain M is kept taut in all positions of the binder by a belt-tightener, N, composed of two rollers journaled in opposite ends of two parallel bars. This belt-tightener 120 is supported by the journal of one of its rollers on the upper end of the upright bar N', the lower forked end of which embraces the hub of the chain-wheel M", and is held at the proper distance from the chain-wheel M' by a 125 bar, N". The bars N' and N" constitute a joint where they are pivoted together, which opens more or less according as the binder is adjusted, and it is evident that the distance from the wheel M" to the wheel M' by the way 130 of the pulleys at said joint, and consequently the tautness of the driving-chain, will be constant, whatever position the binder may occupy.

The operation of the machine can be understood from the foregoing description; but it may be useful to briefly recapitulate so much thereof as relates to the disposition of the grain after it is cut. The cut grain is conveyed across the grain-platform in a direction parallel to the cutter-bar by the carrying-bars B, which constitute the platform-carrier. The packers move the grain in the same direction from the bridge A' onto the binder-table and compact it, as it accumulates, into a gavel, under the compressing-fingers Y', against the binding wire or cord, which stretches from the guide-roller of the tucker to the point of the elevated binding-arm. As soon as a gavel of required size has been accumulated and compacted by the packers the binder shaft is caused to make one rotation, during which the binding-arm first descends with its point through the grain on the elevated bridge A' behind the compacted gavel, encompassing the gavel with the band and bringing the two parts of the band together, the new portion of which band is simultaneously carried by the tucker into the slit in the point of the binding-arm, so that it may be caught by the twister or knotter; then, continuing its motion through the slot in the binder-table, the binding-arm rakes the encompassed gavel across the binder-table while the band is being secured, and finally discharges the bundle into the space between the binder-table and the drive-wheel, through which space it falls to the ground, wholly outside of the frame-work of the machine; after which, still continuing its motion, the binding-arm rises and moves back to its normal position over the grain, which has been accumulated in the meanwhile on the binder-table by the packers.

The term "packers" I use in its technical sense, as applied in automatic grain-binders, to the alternately thrusting or reciprocated and projected and retracted fingers which pack the flowing loose grain by alternate thrusts into a gavel, thrusting beyond the point where the point of the binding-arm passes through the loose grain. I am well aware that such packers have been in use for some time to operate on grain first elevated over the drive-wheel of the harvester and delivered to a binder table or deck on the outside or stubble side of such drive-wheel; but I am the first, so far as I know, to apply such packers to a low-down binder, and by such application of packers I have very materially improved the operation and practical usefulness of low-down binders.

Having thus described my invention, what I claim is—

1. In a low-down self-binder, the combination, substantially as before set forth, of the grain-platform, (comprising means for conveying grain across it,) the low-down binder-table, and an automatic binding mechanism at the delivery side of said grain-platform, and alternately-thrusting packers which positively thrust beyond the point where the point of the binding-arm passes through the grain.

2. In a low-down self-binder, the combination, substantially as before set forth, of the grain-platform, (comprising means for conveying the grain across it,) the low-down binder-table, and an automatic binding mechanism at the delivery side of said grain-platform, alternately-thrusting packers, which positively thrust beyond the point where the point of the binding-arm passes through the grain, and a rotating crank-shaft for operating said packers.

3. In a low-down self-binder, the combination, substantially as before set forth, of the grain-platform, (comprising means for conveying the grain across it,) the low-down binder-table, and an automatic binding mechanism at the delivery side of said grain-platform, the slotted elevated delivery-bridge of said grain-platform, and alternately-thrusting packers, which positively thrust beyond the point where the point of the binding-arm passes through the grain.

4. The combination, substantially as before set forth, of a low-down binder-table, packers which alternately thrust beyond the point where the point of the binding-arm passes through the grain, and a combined binding and discharging arm.

5. The combination, substantially as before set forth, of the platform-carrier, the low-down binder-table, and alternately-thrusting parallel packers, which take the grain and pack it in a gavel on the binder-table.

6. The combination, substantially as before set forth, of the grain platform, the main or drive wheel, the intermediate main frame terminating at the rear on about a line with the front line of the grain-platform, the automatic binder, and the binder-table, supported from the main frame at the delivery side of the grain-platform, a clear space being provided between the binder-table and drive-wheel for the discharge of the bundle wholly outside of the frame-work of the machine.

7. In a self-binding harvester, the combination of a grain-receiving platform, A, overhung from and sustained by a front support, and having an elevated delivery-bridge, A', grain-carriers for conveying the grain transversely across the platform, a shaft for propelling the grain-carriers, the intermediate main frame, F, the main or drive wheel W, and the binder-table A", the said members being arranged, as described, to leave a clear space between the binder-table and the drive-wheel for the free discharge of the bundle, substantially as described.

8. In a self-binding harvester, the intermediate main frame, F, provided with tracks G, and interposed between the inner end of the finger-beam and the main or drive wheel, and having its rear end in line, or nearly so, with the front of the overhung grain-receiving platform, in combination with a binder-table, and a plate, H, carrying a binding mechanism, and adjustable on the tracks of the intermediate main frame, substantially as described.

9. In a self-binding harvester, a grain-receiving platform, A, overhung from and sustained by a front support having an elevated delivery-bridge, A', combined carriers and packers B B', and a single crank-shaft, E, for reciprocating the combined carriers and packers, in combination with the intermediate main frame, F, main or drive wheel W, and binder-table A," arranged, as described, to leave a clear space for the discharge of the bundle between the binder-table and the drive-wheel, substantially as and for the purpose specified.

10. In a self-binding harvester, the intermediate main frame, F, provided with tracks G, and interposed between the inner end of the finger-beam and the main or drive wheel, and having its rear end in line, or nearly so, with the front of the overhung receiving-platform, in combination with the adjustable plate H, standard or post H', bearing-arm H", shaft I, crank I', binding-arm J, and binder-table A", arranged as described, whereby the bundle can be discharged sidewise between the binder-table and the drive-wheel, substantially as and for the purposes specified.

11. In a self-binding harvester, a grain-receiving platform, A, overhung from and sustained by a front support, as described, combined carriers and packers B B', intermediate main frame, F, located forward of the receiving-platform, with its rear portion between the inner end of the finger-beam and drive-wheel W, all arranged as described and for the purposes specified, in combination with a binding-arm and binder-table adjustably mounted on the main frame, a driving mechanism for the binding-arm, and a belt or chain tightener for the driving mechanism, whereby the mechanism is operative in whatever position adjusted, substantially as and for the purposes specified.

12. In a self-binding harvester, a chain-tightener, N, and bars or supports N' N", in combination with the chain M, sprocket-wheels M' M", gear-wheels O O', shaft I, crank I', binding-arm J, and an adjustable support for the shaft and binding-arm located and operating on an intermediate main frame interposed between the main or drive wheel and an overhung receiving-platform, and a binder-table connected with the adjustable support for insuring the driving of the binding-arm, in whatever position adjusted, substantially as specified.

13. In a self-binding harvester, a grain-receiving platform overhung from and sustained by a front support, as described, having horizontal carriers receiving the grain direct from the cutters and delivering the grain to, and packing it in gavels on, a binder-table, an intermediate main frame located forward of the receiving-platform, with its rear portion in line, or nearly so, with the front of the platform and between the inner end of the finger-beam and main or drive wheel, as described, and having a binder mounted thereon, in combination with a seat located outside and at the rear of the drive-wheel for enabling the operator to have the entire mechanism under inspection, substantially as specified.

14. In a grain-binding harvester, the rocking tucker K, located in the slot of the binder-table, the shaft L, crank L', rod L", and crank L", in combination with a binding-arm, J, extension J', link J", support H", bearing-arm H", standard H', shaft I, crank I', and a suitable driving mechanism for the shaft I, said members being constructed and arranged substantially as and for the purpose described.

PLINY F. HODGES.
